UNITED STATES PATENT OFFICE.

EDWARD W. DANIEL, OF ASBURY PARK, NEW JERSEY.

DEVICE FOR SECURING WALL BOARDS AND THE LIKE.

Application filed February 26, 1923. Serial No. 621,192.

To all whom it may concern:

Be it known that I, EDWARD W. DANIEL, a citizen of the United States, residing at Asbury Park, county of Monmouth, and

- 5 State of New Jersey, have invented certain new and useful Improvements in Devices for Securing Wall Boards and the like, of which the following is a specification, reference being had to the accompanying drawings.
- 10 My invention relates generally to securing devices useful in fastening materials or elements in sheet or board form such for example, as in wall of partition building to secure wall boards to a skeleton structure or
- 15 ground work designed for their mounting and support.

My invention is directed in the broadest aspect toward providing a device of the character above defined capable of being applied directly to the studding bars or rods (as the case may be) without requiring any modification or alteration in such bars or rods (such as notching, drilling or slotting) nor the employment of any special tools other than an ordinary hammer or the like to effect attachment to the supporting structure.

Other subsidiary objects of my invention, together with their attendant advantages will become readily apparent from the detailed description which follows of a typical embodiment of my invention, while its scope will be as readily manifest from the appended claims.

In the drawings Fig. I is a fragment of 35 a wall or partition conveniently illustrating how my improved securing devices may be employed in securing the wall boards to the skeleton frame provided for their support.

Fig. II is a detail cross section on an enlarged scale taken as indicated by the arrows II-II in Fig. I; and

Fig. III is a perspective view of the securing device per se.

More especially from Fig. I it will be observed that the securing device of my invention comprises a member 1 in the form of a clip, and a key 6 whereby said clip can be clamped to a suitable support as hereinafter noted. The clip 1 may be briefly described as consisting of a main or body portion 2 which is of channelled cross section as clearly shown in the perspective illustration, and laterally extending wings 3 flanking opposite sides of the body portion and constituting means for engaging the edges of the sheet material or wall boards which are to be

secured. Said wings 3 are grouped in pairs and the components of these groups lie in different parallel planes so that intervals are afforded to accommodate the thickness 60 of the sheets or boards. Directly adjacent the open end of the channel of the body portion, the side walls 4, 4 of the latter are provided with notches or slots 5, 5 which extend downwardly from their upper edges 65 at a slight inclination to the vertical. These notches are designed to receive the key 6 and in conjunction with it serve as a clamping means whereby the clip member 1 may be fastened to the bars or rods of a skeleton 70 framework as hereinafter noted. The securing device of my invention lends itself readily and conveniently to economic manufacture from comparatively thin sheet metal, 75 and may be produced for example, by stamping or cutting a blank of appropriate form which after bending will produce a structure of the configuration hereinbefore described. A clip thus made has the attributes 80 of lightness, pliability, and by virtue of the thinness of the metal requires very little space for its accommodation and is therefore inconspicuous in use as will be obvious from later description. For the same reasons, the key 6 is also preferably constructed from 85 sheet metal.

The manner in which the securing device is used in wall or partition building will be readily understood from Figs. I and II, wherein the skeleton supporting framework 90 which is to serve as a mounting for the wall boards B is shown as consisting of a series of uprights or studs 10 and 10 of channel iron, which which may also include horizontal cross bars or connectors 11, 11 of 95 similar material if greater rigidity should be found desirable or necessary. When in position it will be best observed from Fig. II, that the channelled body portion 2 of the clip 1 embraces the stud 10 while the laterally extending wings 3 respectively lap marginal portions at opposite sides of adjacent boards B thus serving to embrace the board edges and to determine positions of relative alignment for them in the wall or partition. 100 The clip is fixed to the studs or bars of the skeleton supporting structure through clamping action induced by forcing the key 6 into the wedge slots 5, said keys thus serving as a closure for the channel of the main or body portion of the clip and as a keeper to prevent subsequent dislodgment of 105 110

the same, as will be manifest from Fig. II of the drawings. The number of clips used and the mode of their distribution in securing a board will of course be varied in accordance with its size and the nature or type of skeleton framework to which it is to be hung.

While I have shown and described my invention as being especially useful in connection with the mounting of wall boards in wall or partition building, I do not wish to limit myself to such specific use since the same may obviously be employed in many other instances where sheet material is to be hung.

Having thus described my invention, I claim:

1. A securing device of the character described comprising a channel section body portion for embracing an element of a skeleton supporting structure, the legs of said body portion being formed with laterally projecting wings lying in different planes for engaging an edge of sheet material to secure the same to said supporting structure.

2. A securing device of the character described comprising a channel section body portion for embracing a skeleton supporting structure, and opposed stepped wings integral with the channel section legs for engaging the edges of sheet material to secure the same to the supporting structure.

3. A securing device of the character described comprising a main or body portion for embracing a bar or rail of a skeleton supporting structure, and integral laterally extending stepped wings for lapping edge margins at opposite sides of sheet material to secure the same to the supporting structure.

4. A securing device of the character described in the form of a clip constructed of sheet metal comprising a main or body portion for embracing a bar or rail of a skeleton supporting structure, and integral laterally extending wings lying in different parallel planes for lapping edge margins at opposite sides of sheet material to secure the same to the supporting structure.

5. A securing device of the character de-

scribed in the form of a clip constructed of sheet metal comprising a main or body portion for embracing a bar or rail of a skeleton supporting structure, and integral stepped wings projecting laterally at opposite sides of the main or body portion for embracing the edges of sheet material to secure the same to the supporting structure.

6. A securing device of the character described comprising a main or body portion for embracing a bar or rail of a skeleton supporting structure, means for engaging the edges of sheet material to secure the same to the supporting structure, and wedge means for clamping the main or body portion to the bar or rail aforesaid.

7. A securing device of the character described comprising a channelled body portion for embracing a bar or rail of a skeleton supporting structure, means for engaging the edges of sheet material to secure the same to the supporting structure, and a key member cooperating with inclined slots in the side walls of the body portion adjacent the open end of the channel to clamp the device to the bar or rail aforesaid.

8. As a new article of manufacture, a securing device for wall-boards having a channel-section body portion and opposingly directed pairs of stepped wings laterally projecting from each leg thereof, said stepped wings affording intervals for the accommodation of aligning sheets of wall-board.

9. As a new article of manufacture, a securing device for wall-boards having a channel-section body portion and opposingly directed pairs of stepped wings laterally projecting from each leg thereof, said stepped wings affording intervals for the accommodation of aligning sheets of wall-board, and inclined slots adjacent the outermost wings for the reception of a clamping member whereby the device is secured in use.

In testimony whereof I have hereunto signed my name at Philadelphia, Pennsylvania, this 23rd day of February, 1923.

EDWARD W. DANIEL.
